UNITED STATES PATENT OFFICE.

EZRA ESTEP, OF SANDWICH, ILLINOIS.

MOLDING APPARATUS.

No. 902,062.

Specification of Letters Patent.

Patented Oct. 27, 1908.

Application filed May 4, 1908. Serial No. 430,780.

To all whom it may concern:

Be it known that I, EZRA ESTEP, a citizen of the United States, and resident of Sandwich, county of Dekalb, and State of Illinois, have invented certain new and useful Improvements in Molding Apparatus, of which the following is a specification, and which are illustrated in the accompanying drawings, forming a part thereof.

10 The invention relates to molding apparatus, and more especially to that intended for bench use wherein the apparatus is manipulated by hand.

The object of the invention is to provide 15 simple and improved apparatus for hand molding, the improvements being intended more particularly to facilitate the withdrawing of the patterns from the finished mold.

20 In the accompanying drawings Figure 1 is a sectional view of apparatus embodying the invention, the plane of the section being indicated by the line 1—1 on Fig. 2; Fig. 2 is a plan view of the same; Fig. 3 is a diagonal 25 sectional view of a mold produced by the apparatus illustrated in Figs. 1 and 2; Fig. 4 is a bottom plan view of a pattern plate and stripping plate shown in Figs. 1 and 2; and Figs. 5 and 6 are detail sectional views showing the parts of the apparatus in different 30 positions.

The cope and drag members of a flask intended for hand molding are illustrated in the drawings at 10 and 11, respectively. 35 These flask members are preferably of the openable or snap flask type, each being a two-part rectangular frame, the parts of the frame being hinged together at one of its corners, as indicated at 12, and connected at 40 the diagonally opposite corner by a clasp or latch, designated 13. The two flask members 10 and 11 fit together in the customary manner by means of intercalating dowel pins and apertures, designated respectively 45 14, 14, and 15, 15.

In carrying out the invention a pattern plate 16 is provided. This pattern plate is adapted to be interposed between the parts of the flask during the formation of a mold, and as 50 shown comprises a body portion 17, coextensive in area with the meeting faces of the members 10, 11, and end flanges 18, 19, which project beyond the margins of the flask members when the parts are assem-

bled. Each of the end flanges 18, 19, is provided with an aperture, as 20, 21, for receiving one of the dowel pins of the flask.

55 Patterns 22 are formed upon the pattern plate 16, the cope and drag portions of the patterns being upon opposite sides of the plate. As shown the patterns provided are for a plurality of mongrel gears, the cope portion of each disposed upon the opposite face of the plate but in line with the body of the corresponding pattern comprising only one 60 of its core prints 23. The patterns 22 and the plate 16 are preferably formed of metal, and the patterns are secured to the plate by uniting the two parts thereof on opposite 65 sides of the plate by a screw 24.

70 A stripping plate 25 is used in connection with the pattern plate 16 to bear upon the face of the sand mold formed in the flask during the withdrawal of the patterns 22. This stripping plate is preferably coextensive 75 in area with the pattern plate 16, and as shown its body portion is apertured, as indicated at 26, 27, 28 and 29, to fit snugly over the drag portion of each of the patterns 22 against the face of the pattern plate. 80 Flanges 30 and 31, formed on the stripping plate and corresponding to the end flanges 18, 19, of the pattern plate, are apertured to receive the dowel pins 14 of the flask. The drag portion of each of the patterns 22 is 85 provided with a shank or base 32 for separating it from the plate 16, whereby the whole of that part of the pattern intended to produce an impression in the sand mold formed in the flask 10, 11, protrudes through 90 the stripping plate 25 when the latter is in contact with the pattern plate 16.

95 As shown, the pattern plate 16 and stripping plate 25 are connected by bolts, as 33, 34, Figs. 2 and 5, these bolts being firmly secured in one of the plates, as the pattern plate 16, and slidingly engaging the other plate to permit a separation of the plates for a limited distance, preferably equal to the 100 depth of the vertical walls of the patterns 22.

105 Handles 35, 36, are provided for lifting the pattern plate 16 and the stripping plate 25, and for separating the plates. As shown, each of these handles is pivoted to the stripping plate, as at 37, 38, and is provided with a cam shoulder 39 for bearing against the face of the pattern plate to separate the plates when the handle is swung to the po-

sition of service indicated in Fig. 5 of the drawings.

In use the flask members 10 and 11 will be assembled with the pattern plate 16 and 5 stripping plate 25 interposed therebetween, the handles 35, 36, being folded to the position illustrated in Figs. 1 and 6 to permit the stripping plate 25 and the pattern plate 16 to be so drawn together that the whole of 10 that part of each of the patterns 22 intended to produce an impression in the sand mold to be formed protrudes through the stripping plate. The drag portion 11 of the flask will then be filled with sand in the usual 15 way, and the sand rammed against the face of the stripping plate 25, which, as shown, has formed thereon a rib 48 (Fig. 4) leading to each of the patterns 22 for effecting a suitable gating of the mold. The apparatus 20 will then be overturned to present the cope member 10 of the flask uppermost. This part of the flask will be filled with sand and the sand rammed against the back of the pattern plate 16, a sprue 41 being preferably 25 introduced to provide a suitable opening for pouring, which communicates with the gates formed in the drag portion of the flask by the rib 48 when the pattern plate has been withdrawn and the parts reassembled, as hereinafter described. The cope 30 portion of the flask may now be removed in the usual way, and the patterns 22 will then be withdrawn from the sand contained in the drag portion 11 of the flask by a raising 35 of the handles 35, 36, to the position of service illustrated in Fig. 5 of the drawings, whereby the pattern plate 16 is separated from the stripping plate 25, the latter bearing upon the face or parting of the sand during 40 this operation and serving to prevent injury to the edges of the mold by the withdrawing of the patterns. The pattern plate 16 and stripping plate 25 may now be wholly removed by the use of the handles 35, 36, 45 and the parts of the mold reassembled for pouring by fitting together the parts of the flask, the flask being then preferably removed from the mold by releasing the latches 13 and opening the hinges 12.

50 If desired handles 42, 43, may be employed for raising the cope member 10 of the flask. As shown these handles are pivoted to flanges 44, 45, formed upon the ends of the flask, as indicated at 46, and each is continued beyond its pivot, as shown at 47, to react upon the back of the pattern plate 16, after the manner of a lever for raising the cope portion of the flask when the handles are turned to the upright position illustrated 55 in Fig. 6 of the drawings.

As shown, by reason of the angular form of the handles 35, 36, these handles serve when turned to the position illustrated in Fig. 5, to maintain the pattern plate 16 and 60 stripping plate 25 in separated relation.

When the handles 42, 43 are turned to the position illustrated in Fig. 6, their inner ends 47 serve as legs for supporting the cope member 10 of the flask.

I claim as my invention—

- 70 1. In combination, a pattern plate for bench molding, a stripping plate coöperating therewith, and a pivoted handle for lifting the plates adapted to react between the plates to separate them when swung to the position of service.
2. In combination, a pattern plate adapted to be interposed between the cope and drag members of a two-part molding flask, a stripping plate coöperating with the pattern plate, and a pivoted lever reacting between the plates to separate them.
3. In combination, a pattern plate for bench molding, a stripping plate coöperating therewith, a pivoted handle for lifting the plates adapted to react between the plates to separate them when swung to the position of service, and a bolt limiting the separation of the plates.
4. In combination, a molding flask for 90 bench use, a pattern plate fitting the mouth of the flask, and a pivoted handle for lifting the flask adapted to react on the pattern plate to separate it from the flask when swung to the position of service.
5. In combination, a two-part molding flask for bench use, a pattern plate fitting the flask, a stripping plate coöperating with the pattern plate, and a pivoted handle for lifting the pattern plate adapted to react between the pattern plate and the stripping plate to separate them when swung to the position of service.
6. In combination, a two-part flask for 100 bench molding comprising a cope and a drag, a pattern plate fitting between the parts of the flask, a stripping plate coöperating with the pattern plate, a pivoted handle for lifting the cope of the flask adapted to react on the pattern plate to separate it from the cope of the flask when swung to the position of service, and a pivoted handle for lifting the pattern plate adapted to react between the pattern plate and the stripping plate to separate them when swung to the position of service.
7. In combination, a two-part molding flask, and a pivoted handle for lifting one part of the flask adapted when swung to the position of service to react between the parts of the flask to separate them.
8. In combination a molding flask comprising cope and drag members, and a lever pivotally attached to one of the flask members and engageable with the other member to separate the two members.
9. In combination, a pattern plate for 115 bench molding, a stripping plate coöperating therewith, and a lever pivoted to one of the plates and bearing upon the other, the bearing surface of the lever being of angular form
- 120
- 125
- 130

whereby the lever serves for separating the plates and for maintaining the plates in separate relation.

10. In combination a pattern plate for bench molding, a stripping plate coöperating therewith, a bolt limiting the separation of the plates, and a lever pivoted to one of the plates and bearing upon the other, the bear-

ing surface of the lever being of angular form whereby the lever serves for separating the 10 plates and for maintaining the plates in separated relation.

EZRA ESTEP.
